UNITED STATES PATENT OFFICE.

MYLES P. FILLINGHAM, OF ANSONIA, CONNECTICUT, ASSIGNOR TO BIRMINGHAM IRON FOUNDRY, OF DERBY, CONNECTICUT, A CORPORATION.

VULCANIZING-PRESS.

1,004,864.

Specification of Letters Patent.

Patented Oct. 3, 1911.

Application filed May 8, 1911. Serial No. 625,797.

To all whom it may concern:

Be it known that I, MYLES P. FILLINGHAM, a citizen of the United States, residing at Ansonia, in the county of New Haven and State of Connecticut, have invented a new and useful Improvement in Vulcanizing-Presses; and I do hereby declare the following, when taken in connection with the accompanying drawings and the letters 10 of reference marked thereon, to be a full, clear, and exact description of the same, and which said drawings constitute part of this specification, and represent, in—

Figure 1 a side view of a press constructed in accordance with my invention. Fig. 2 a sectional view of the same with the press tank closed and the table in a depressed position. Fig. 3 a similar view with the press tank lowered and the table raised with the 20 cap supported above it. Fig. 4 a top view showing the cap in its locked position with relation to the tie-rods. Fig. 5 a plan view of the head and cover. Fig. 6 a sectional view of the ram cylinder showing a top view 25 of the piston thereon. Fig. 7 a vertical sectional view of the piston. Fig. 8 a sectional view on the line *a—b* of Fig. 7. Fig. 9 a plan view of the head formed with an elliptical opening. Fig. 10 a plan view of an 30 elliptical cover therefor. Fig. 11 shows two bars pivoted together and adapted to be used as a substitute for the cover shown in Fig. 10.

This invention relates to a vulcanizing 35 press of the type in which hydraulic pressure is employed and in which rubber products may be vulcanized, and particularly a press in which tires for automobiles and other vehicles may be vulcanized; the object of the invention being a simple construction which facilitates the charging and emptying of the press; and in which the necessary power is obtained with the minimum amount of strain on the mechanism; and the 40 invention consists in the construction herein-after described and particularly recited in the claims.

In carrying out my invention, I employ a 45 press tank 2 of suitable size which is adapted to move vertically on a ram cylinder 3 which cylinder passes through a piston-box 4 and is supported by a base 5. Around the upper end of the tank 2 is a head 6 which is connected with the piston-box 4 by four 50 tie-rods 7. The upper end of the ram cyl-

inder 3 forms a table support 8 upon which a table 9 rests, and this table is mounted at the upper end of a ram 10 which extends downward into the ram cylinder to which water is admitted through a port 11 near the 60 base 5. In the head 6 is a central opening 12, and in the edge of the opening are a series of notches 13 more or less in number. Through the opening a cover 14 may be inserted the cover being formed with outwardly projecting fingers 15 corresponding in position to the notches 13 so that the cover may be passed through the head, and when passed through may be turned so that the fingers 15 engage with the edge of the 70 cover between the notches 13. Resting upon the head is a cap 16 which is formed with four holes 17 of sufficient size to allow the cap to pass over the nuts 18 on the upper ends of the tie-rods 7, and opening into these 75 holes 17 are slots 19 which permit the cap to be rotated slightly so as to pass between the nuts 18 to firmly interlock the cap with the head. Preferably the cover 14 will be connected to the under face of the cap 16 by 80 screws 20 passing upward through the cover and into the cap so that the cover may have a slight vertical movement with respect to the cap which will be turned with it and so that when the cap is turned to interlock with 85 the nuts 18 the cover will be turned to lock with the head 6. To support the cover I attach to each of the tie-rods 7 a bracket 21, and the cover is formed with four downwardly extending fingers 22 in the lower 90 part of which rollers 23 are mounted and adapted to ride on the brackets. One of the brackets 24, however, will be formed with a rack 25 and the roller 26 adjacent thereto will be formed as a pinion to engage with 95 the rack and is rigidly secured to a short shaft 27 to the outer end of which is fixed a hand-wheel 28 and so that by turning the hand-wheel the cap will be caused to rotate. Preferably and as herein shown, the cap will 100 be provided with a suspension hook 29 by which the cap may be supported from any convenient point as will hereinafter appear.

On the ram cylinder within the piston-box 4 is a piston which consists of a ring 105 30 resting at its lower end on a collar 31 formed integral with the ram cylinder 3 which is also formed with an annular lip 32 above the collar which lip is formed with notches 33 to receive bolts 34 the heads of 110

which rest between the lip 32 and the collar 31, the bolts extending up through the ring 30, and this is held in place by a removable collar 35 formed with the round holes 36 adapted to set over the nuts 37 on the bolts 34, and with slots 38 opening from said holes so that if the removable collar is slightly turned it will be interlocked with the nuts. The removable collar will also be provided with perforations 39 which when the collar is turned to clear the nuts 37, will register with threaded holes 40 into which screw eyes may be turned and by which the ring may be lifted out of the piston-box, it being understood that the holes in the ring through which the bolts pass will be sufficiently large to clear the nuts 37. In the bottom of the piston-box is a port 41 for the admission of water; and in the top of the box is a port 42, the first entering below the piston, and the other above it. The ends of the piston-box will be closed by covers 43, 44, and these covers as well as the bottom of the press tank will be provided with a stuffing box 45 of usual form. Between the head and the cap, I arrange a packing-ring 46, between the table and the table-support a packing-ring 47, and around the ring 30 I insert two leather packings 48. The tank 2 may be surrounded by a jacket 49 into which steam may be admitted so as to vulcanize by dry process.

To load the press, the cap 16 is turned so as to clear the nuts 18, and this turning of the cap turns the cover 14 so as to disengage it from the head 6. Water is then admitted through the port 41 into the piston-box below the piston, and this depresses the piston-box drawing the press tank downward, and it is depressed until the table 9 is exposed at the top of the tank. Mold boxes 50 are then placed upon the table, one on the top of the other if a number are to be inserted; and when the desired number of molds are placed upon the table the tank is raised by admitting water through the port 42 above the piston and letting water escape through the port 41 below the piston so as to lift the piston-box and raise the press-tank. The cover and the cap are then restored to place. If there is then a space between the upper mold and the cover, the ram 10 will be raised by admitting the water through the port 41 so as to crowd the molds up against the cover and hold the cover up against the under face of the head. Water will then again be admitted through the port 41 drawing the press tank downward, and forcing the cover to the top of the uppermost mold, which molds will be compressed between the cover and the head with a force equal to the weight of the tank and press box in addition to the hydraulic pressure. Steam is then admitted to the press tank in the usual

way through the pipe 51 to vulcanize the articles in the press. When properly cured the cap and cover are again removed and the press depressed to permit the molds to be readily removed. It will be noted that this construction permits the mold to be inserted into the top of the press tank or transferred from a suitable platform directly to the table as the table may be moved up or down independent of the press tank. 75

Instead of connecting the cover 14 with the cap 16, it may be formed independent thereof, and the opening in the head may be elliptical to receive an elliptical cover 52. By turning this cover, it is readily inserted 80 through the head and turned so that its edges engage with the under face of the head, or instead of forming the cover as in the form of a disk or plate it may be in the form of two bars 53 and 54 which 85 are pivoted together so that they may be turned to permit the bars to be inserted through the hole in the head, and then turned at right angles to engage with the under face of the head. 90

I claim:

1. In a vulcanizing press, the combination with a ram-cylinder carrying a piston, a piston-box movable vertically with respect to said piston, tie-rods extending 95 upward from said piston-box, a press tank supported by said rods, a cover for said tank, a cap detachably connected with said tie-rods, a table within said press-tank, said table mounted at the upper end of a ram 100 which extends into said ram cylinder.

2. In a vulcanizing press, the combination with a ram-cylinder carrying a piston, a piston-box movable vertically with respect to said piston, tie-rods extending upward from said piston, a press-tank provided with a head supported by said rods, said head formed with an opening, a cap detachably connected with said tie-rods, a cover connected with said cap and adapted 110 to close the opening in said head, a table within said press-tank, said table mounted in the upper end of the ram which extends into said ram-cylinder. 110

3. In a vulcanizing press, the combination with a ram-cylinder carrying a piston, a piston-box inclosing said piston and provided with ports at opposite ends, tie-rods mounted on said piston-box and extending upward therefrom, a press-tank having a head and mounted upon the upper ends of said rods said head formed with an opening, a cover adapted to close said opening and bear against the under face of said head, a cap connected with said tie-rods over said head, a table within the tank, and a ram supporting said table and extending into said ram-cylinder. 125

4. In a vulcanizing press comprising a piston-box, tie-rods extending upward 130

therefrom, brackets mounted on said tie-rods, a press-tank having a head mounted on the said tie-rods above said brackets, said head formed with an opening, a cover 5 adapted to close said opening and bear against the under face of the head, a cap connected with said tie-rods over said head and formed with downwardly extending arms carrying rollers adapted to bear upon 10 said brackets, one of said brackets having a rack and one of the rollers toothed to engage therewith, and means for turning the said toothed roller whereby the cap and cover are rotated, a table within the tank, 15 and an arm supporting said table and extending into said ram-cylinder.

5. In a vulcanizing press, the combination with a ram-cylinder carrying a piston, a piston-box inclosing said piston and provided with ports at opposite ends, tie-rods 20 mounted on said piston-box and extending upward therefrom, nuts applied to the upper ends thereof, a press-tank having a head and mounted on said tie-rods, a cap formed 25 with holes adapted to set over said nuts on the tie-rods and with slots which permit the cap to be turned so as to pass beneath said nuts whereby the cap is locked in place.

6. In a vulcanizing press, the combination with a vertically supported ram-cylinder

der formed with an annular collar, a piston supported thereby, a piston-box inclosing said piston, tie-rods secured to and extending upward from said piston-box, a press-tank supported by said tie-rods, a cover for 35 said tank, and a cap interlocked with the tie-rods above said head.

7. The combination with a vertically supported ram-cylinder formed with an annular collar and an annular lip above the collar, a ring resting on said collar and secured by bolts passing upward through said lip, 40 said bolts provided at their upper ends with nuts, a removable collar formed with holes adapted to set over said nuts and with slots 45 which permit the removable collar to be slightly rotated beneath said nuts whereby the ring is clamped in position, a piston-box inclosing said piston, tie-rods secured to and extending upward from said piston-box, a 50 press tank mounted on said tie-rods, a cover for said tank, and a vertically movable table within said tank.

In testimony whereof, I have signed this specification in the presence of two subscribing witnesses. 55
